HOLE FORMING TOOL

Filed Feb. 19, 1938

UNITED STATES PATENT OFFICE

2,176,943

HOLE FORMING TOOL

William O. Reeser, Dayton, Ohio

Application February 19, 1938, Serial No. 191,467

5 Claims. (Cl. 164—101)

(Granted under the act of March 3, 1883, as
amended April 30, 1928; 370 O. G. 757)

The invention described herein may be manufactured and used by or for the Government for governmental purposes, without the payment to me of any royalty thereon.

5 My invention relates generally to tools for sheet metal work, or other sheet material, and particularly to tools for cutting and enlarging holes in such sheets.

A particular use is found in electrical construction work for the enlarging of "knock-out" holes in electrical junction or outlet boxes to receive a larger size of conduit than provided for by the original "knock-out" in the box. Heretofore, the usual way of accomplishing this objective has been by laboriously filing the hole to the desired increased diameter. A tubular punch as struck by a hammer cannot be used for lack of suitable backing, and furthermore, it is difficult to obtain a clean, smooth hole, if the metal is of

20 such gauge or thickness as to require more than one blow of the hammer. A still further problem is that, in many instances, there is insufficient space for the use of striking means, such as a hammer, or for the use of boring means. The 25 use of my tool in this type of work often eliminates the necessity for removing and replacing junction boxes in confined places, thereby saving much cost of labor and materials. It is therefore an object of my invention to provide 30 a tool useful for making holes in sheet metal in places and under conditions inaccessible to large and bulky tools, and where there is insufficient space for the use of striking means, such as a hammer.

35 Although my invention is defined as a tool for cutting or enlarging holes in sheet metal, its primary object is to accomplish a hole of given diameter with a clean, burrless cut, and it is only incidental to this object, that it is necessary to 40 make a smaller hole by any ordinary means before the application of my tool for accomplishing the hole of desired diameter. In the case of holes in electrical boxes, the smaller hole is obtained by striking out the "knock-out" portion, if this 45 "knock-out" is satisfactorily located for the center of the hole. Otherwise, it is necessary to first bore or punch a smaller hole than the "knock-out" at the desired center. Heretofore, the instruments or tools used to make holes of a 50 given diameter, such as drills, punches, or dies, have left a metal burr, or rough edge, on the far side of the sheet metal. This rough edge left on holes is particularly objectionable in the case of enlarging the "knock-out" holes of the electrical 55 junction or outlet boxes, and must be filed off.

Besides being a source of dangerous injury to the fingers of workmen, the burr prevents tightening of the lock nut on the conduit to a flush rigid fit with the side walls of the box. Since this lock nut often may be used to protect the contents of the box from the elements, or to provide an electrical contact for ground in some systems, it is essential that this nut should fit tightly against the box. In the case of electrical boxes in aircraft, where aluminum fittings and nipples are used, the rough edge on the hole of a box, in co-operation with a loose connection, will wear or cut through the aluminum fitting. I have succeeded in making holes without this objectionable feature by first making a small hole, less than the desired diameter, and then completing the removal of the remaining metal by the application of the tool I have invented, as hereinafter described.

5 A further object of my invention is to provide 20 a tool for making holes in soft metals, such as aluminum, which exhibit a tendency to become distorted or "grow" at the periphery as a reaction to the application of impact. Because of this phenomenon exhibited by such a metal as 25 aluminum, it is difficult to make a hole in a sheet of small dimensions by the use of a tubular punch struck by a hammer without distortion of the periphery of the sheet due to the lateral displacement of the material by the walls of the punch. 30 Where it is necessary that the periphery be kept in its original alignment or dimensions, or in the case of electrical junction boxes, the expanded portion must be removed by filing or grinding. 35 Since the cutting action of my tool is accomplished gradually and without impact, this phenomenon of "growth" is avoided, and no remedial action is needed.

40 A still further object of my invention is to provide in a tool of this character a punch die 40 capable of self-centering in a hole to be enlarged by said tool.

The above and still further objects and advantages of the invention will become apparent 45 from a study of the following specification taken in connection with the accompanying drawing wherein like reference characters designate corresponding parts throughout the several views, and wherein:

50 Fig. 1 is a vertical section through one embodiment of my tool, assembled with the metal blank in position to be cut;

55 Fig. 2 is an exploded view of the same embodiment of my tool;

Fig. 3 is a view similar to Fig. 1 showing another embodiment of my tool;

Fig. 4 is a bottom plan view of Fig. 3;

Fig. 5 is a fragmentary view partially in section 5 similar to Fig. 1 showing another embodiment of my invention;

Fig. 6 is a side elevation view of one form of cutting die employed in my invention;

Fig. 7 is a bottom plan view of the same die;

10 Fig. 8 is a perspective view of one form of die used in my invention;

Figs. 9, 10, and 11 are section views showing progressive stages in the cutting of a metal blank as accomplished by my invention.

15 Fig. 12 is a fragmentary section view showing a further arrangement of the cutting dies.

Now referring to the drawing in detail, it will be seen from Figs. 1 and 2 that my tool consists of a driving screw member 1; having at one end 20 threadedly mounted thereon an annular support or carrier 2; a washer 3 carried on the element 2 and loosely mounted on said driving screw; a tubular cutting die 4, provided with a bevelled knife-like cutting edge 5, surrounding said driving screw, mounted on said washer and spaced and centralized with respect to said driving screw by means of an annular spacer or guide 6, said spacer being of a length less than the tubular die 4 in order to provide a recess 7 in the top portion 25 sheet material; and a cutting die 9 comple- thereof to receive the slug 8 to be cut from the mentary to the die 4, provided with a bore 10 to receive the driving screw in close fitting and sliding relation, and further provided with a 30 tapered or bevelled portion 11 on the end opposite the normal cutting face 12. The driving screw is provided with an abutment 13, which limits the travel in one direction of the die 9. This abutment is preferably made an integral 35 part of the driving screw and is in the form of a square-shaped head to enable engagement by a suitable tool for effecting a relative rotation between the driving screw 1 and the carrier 2, which is also square shaped, to likewise enable engagement by a proper tool. The shaft of the driving screw should be of sufficient length to permit 40 relative displacement between the cutting members 4 and 9 for receiving therebetween various thicknesses of metal or other materials to be operated on.

It is preferable in the above assembly that the cutting member 9 should have a diameter only a few thousandths less than the inside diameter of the tubular die 4. It is desirable to make the 45 guide 6 as close fitting with the tubular die 4 as practically possible, as it is by means of the guide through its bore 14 cooperating with the driving screw 1 that the tubular die 4 is kept in alignment with the cutting member 8. The bore 14 50 in the guide 6, and the bore 10 in the cutting member 9 should be as close fitting as possible to the driving screw 1 in order to assure good alignment. The washer 3 should be of considerably larger diameter than the tubular die 4 in 55 order to serve as a support for dies of various diameters, and its bore 15 should be fairly close fitting to the driving screw 1 but need not be made with the precision of the bores in the guide or in the cutting member. The washer should 60 be of sufficient thickness to be rigid for all operations. A few thousandths of an inch clearance is desirable between cutting member 9 and the inside diameter of the tubular die 4 in order to provide for some degree of self-adjustment be- 65 tween the two members when they are being 70

forced together by the advance of the carrier 2 on the driving screw 1, upon relative rotation therebetween.

The normal operation of my tool as illustrated in Fig. 1 consists in inserting the driving screw 1 with the die 9 mounted thereon in the hole 16 in the sheet material or blank 17 to be enlarged to the diameter of the die, said hole having been previously formed in the sheet material or work. The spacing guide 6, tubular die 4, washer 3, and carrier 2 are next mounted on the driving screw on the side of the material opposite the die 9 in the order named. The threaded carrier 2 is then advanced on the threaded portion of the shaft of the driving screw 1 by relative rotation accomplished by engaging the carrier 2 and the square head of the driving screw by means of suitable tools, thereby urging the tubular die 4 and cutting member 9 towards each other and against the metal blank, shearing from the sheet material the portion 8 of said material or blank under the cutting member 9, as shown in section views, Figs. 9, 10, and 11.

Although the advantages of my tool as a portable hand tool for enlarging and cutting holes in confined or limited areas may be obtained by the use of a flat or right-angled cutting edge on the tubular die 4, or any other conventional type cutting edge in lieu of the bevelled knife-like edge 5, it has been found that this bevelled 30 edge 5, which might also be described as the surface formed by the intersection of a hollow cylinder and a right cone concentric therewith, enables the successful operation in making a hole that is clean cut and free from any burr or rough 35 edge. As a result of this knife-like edge provided on the tubular die 4, the cutting is done in the manner shown in Figs. 9, 10, and 11.

The first application of pressure by means of relative rotation between the carrier 2 and the driving screw 1 forces the knife-like edge 5 of the tubular die 4 into the metal blank 17. As the bevelled edge 5 of the die 4 is driven deeper into the blank, progressively increasing resistance is set up as the area of said die in contact with said metal blank is constantly increasing. Therefore, the tubular die 4 is forced into the metal to a depth where the resistance encountered is equal to the pressure required to shear the entire portion to be cut by the cutting member 9. This 40 position is indicated in Fig. 9. In Fig. 10, the pressure between the dies is now sufficient to force the cutting die 9 into the blank while the die 4 is maintained in a fairly constant relation to said sheet material, and continued relative 45 rotation of the carrier will complete the shearing of the metal blank, and the portion 8 of the metal blank under the die 9 will be forced into the recess 7 in the upper end of the die 4. It is to be noted that due to the position of the tubular die 4 imbedded in the metal blank, the final 50 shearing of the metal portion being cut out is accomplished within the plane surfaces of the blank of material as shown in Fig. 11, and that consequently there will be no burr protruding 55 from the metal blank as in the case of ordinary dies, wherein the flat surface of the cutting member 9 would ordinarily cooperate against a right-angled cutting edge on a base die in the position of the tubular die 4. The shearing as accomplished by my invention is not only confined to the area on the inside of the hole, but is also 60 complete, since the cutting member 9 is actually drawn within the inside diameter of the tubular die 4 as a final process in the cutting. In this 65 70 75

respect, it again differs from the operation of ordinary dies having right-angled surfaces for co-operating edges, as in a punch press wherein the shearing of the cut-out portion is not completed until the cutting member has reached the opposite side of the metal blank and there is no further cutting action required or possible in co-operation with the base die, but the metal portion is definitely torn from the blank upon the incipient approach of the cutting member or die to the base die.

There is a further advantage of this type of combined cutting and shearing operation performed by my tool over the straight shearing operation as performed by ordinary dies, in that the original thickness of the blank to be cut is reduced to the extent that the tubular die 4 penetrates into the blank 17, and, the resulting thickness of metal being less than its original thickness, the force thereby required to shear said material is accordingly less.

Another novel variation in the use of my tool while being used to enlarge holes is to locate the center of the enlarged hole with respect to the center of the already formed hole. Adapting the principle that a cone will automatically seek the mean center of the hole into which it is inserted, I have provided cutting member 9 with a conical surface on its reverse side, so that, when inverted, it will engage the sides of the already formed hole while the dies are being aligned. In order for the tool to work in this manner, it is necessary that the diameter of the conical section of said die at its minimum cross section be less than the diameter of the already-formed hole. Having assembled the dies in this relation, the new hole is cut by urging the dies toward each other in the same manner as specified in the normal operation of the tool.

The cutting action is illustrated in Fig. 12 wherein the aperture 16 in the metal blank is larger than the minimum cross section of the conical faced cutting member 9, thereby permitting the conical face 11 to enter and center itself in the hole 16. The first application of pressure causes the bevelled knife edge 5 of the female die 4 to penetrate into the blank, in the same manner as described for the operations of the tool as shown in Fig. 1, until the resistance induced thereby is equal to the force required to shear the slug 8 from the blank. In the meantime, the cutting member 9 has been bending the slug portion 8 of the blank to conform to the contour of the conical face 11 of the member 9. Thereafter, continued application of pressure between the members 4 and 9 will cause the male member 9 to complete the severance of the slug by a shearing action similar to that shown and described in connection with Figs. 10 and 11.

It is obvious that different sized holes may be cut by using with the driving screw 1, washer 3 and carrier 2 sets of complementary dies 4 and 9 of varying diameters together with a spacer 6 of correspondingly varied diameter.

Having thus described the principle and the operation of my tool, I wish to set forth several other embodiments and their advantages. Fig. 3 shows a modification similar to Fig. 1 except that the tubular die 4 and the washer 3 have been made integral with the carrier 2, of Fig. 1, forming one member 18, and since it is centrally disposed by the carrier, the spacer 6 is no longer needed. Since there is no removable part corresponding to the inside diameter of the tubular die, it is necessary to provide opportunity for re-

moving the cut-out portion 8 of the material which might become lodged in the recess 19. Therefore, I have provided keyways or slots 20, shown in Fig. 4, on opposite sides of the tapped bore in the base of the combined carrier-die 18, into which a suitable flat instrument might be inserted and used as a punch in removing the cut-out portion. 5

Likewise, the head of the driving screw 13 and the cutting member 9, as shown in Figs. 1 and 2, 10 may be combined to form one integral piece similar to the part 21 shown in Fig. 5. This combination of driving screw head and cutting die into one integral part is preferably not used with the integral tubular die, washer, and carrier 18, 15 as shown in Fig. 3, since there would then be no spacing member 6 to provide a surface for the rotation of the driving screw head other than the metal blank of the material itself. An advantage of these embodiments occurs where a single sized 20 hole is constantly being made. Then, one of these combinations, resulting in the reduction of the number of parts, would be preferred to the multi-part tool as shown in Figs. 1 and 2. 25

Fig. 5 illustrates an embodiment of my invention similar to that shown in Fig. 1 except that the cutting member 9 and fixed head 13 of the driving screw 1 have been replaced by one integral part 21 with a portion 24 in this arrangement corresponding to the arrangement of the 30 cutting member 9 in Fig. 1, but made larger than the diameter of the tubular die 4. Therefore, the principle of operation of this embodiment varies from that of the embodiment of Fig. 1 in that the enlarged hole is cut by forcing the 35 tubular die 4 completely through the blank 17 and against the base, or portion 24. It is to be understood that the hole cut in this instance will not have a cylindrical wall, but will be forced into a conical surface because of the conical shape of 40 the cutting edge of the tubular die 4, as shown at 25. It will thus be observed that the use of this embodiment will be limited to occasions where the interior shape of the hole is of no moment, or where such countersink shape is desired, and 45 also it is to be observed that the use of this embodiment of the invention, since it requires greater force to drive the tubular die 4 through the metal than in the embodiments where a cutting member is used in cooperation with the tubular 50 die 4, will be limited to soft metals such as aluminum, zinc, etc., or relatively thin blanks.

Another variation in my invention is shown in Figs. 6 and 7, wherein a cutting member to be used in lieu of the cutting member 9 is constructed with its cutting face composed of four helical surfaces of equal pitch, with the pitch path of the surfaces in successively reversed arrangement. The lines 22 are the most external points on the cutting face of said die, and the lines 23 constitute the points of greatest recession on the face of said die. The advantage of a cutting member of this structure is that in the cutting of harder blanks or blanks of more than ordinary thickness, when the pitch of the helix is equal to 60 or greater than the thickness of the blank to be cut, the force is not applied on the entire surface at one time, but only at the two points 22 at the beginning of the operation, and at no more than four points at any time thereafter until 65 the completion of the operation when the force is applied again through the two points 23. The effect of this application of force is somewhat similar to the effect of cutting with a pair of scissors, in that, in principle, the cutting is ac- 70 75

complished at only one point along a line at a time.

This same principle may be accomplished by using the normal cutting member 9, but varying the plane of the cutting edge of the normal tubular die 4, to a shape as shown in Fig. 8, wherein the bevelled surface constituting the cutting edge 26 is formed as by the intersection, with a cylinder, generated by two diametrically opposed elements of a right cone concentric with the cylinder, while the axis of the cylinder is progressively moved axially in one direction through ninety degrees of rotation of the conical elements and then, the axial progressive movement is reversed through the next ninety degrees of rotation.

It is to be observed that there is no advantage to be obtained by using a cutting member, as shown in the embodiment illustrated by Figs. 6 and 7, in combination with a tubular die, as illustrated in Fig. 8, the use of one or the other of said embodiments accomplishing the desired purpose.

It is believed that the many advantages of a hole enlarging tool constructed in accordance with the present invention will be readily understood, and although preferred embodiments of the invention are as illustrated and described, it is to be understood that further modifications and changes in the details of construction may be resorted to which will fall within the scope of the invention as claimed.

What is claimed is:

1. A hand tool for cutting holes in sheet material, comprising, a male die, a female die, said dies having cooperating cutting edges and being adapted to receive a blank of said sheet material therebetween, said female die having an annular bevelled cutting edge with the surface of the bevel converging toward and intersecting with the inner surface of the die, said bevel being of such pitch that it has less resistance than the male member to relative motion for a predetermined depth of cut, but has a greater resistance than the male member beyond said depth of cut to thereby provide a severance of the material intermediate of the plane surfaces thereof, means for aligning said dies including a driving screw, and means cooperating with said driving screw for moving said dies relatively towards each other.

2. A hand tool for forming holes in sheet material comprising a cutting member, a female die, said die and said cutting member having cooperating cutting edges and aligned bores therein and being adapted to receive a blank of said sheet material therebetween, said female die having an annular bevelled cutting edge with the surface of the bevel converging toward and intersecting with the inner surface of the die, said bevel being of such pitch that it has less resist-

ance than the male member to relative motion for a predetermined depth of cut, but has a greater resistance than the male member beyond said depth of cut to thereby provide a severance of the material intermediate of the plane surfaces thereof, a driving screw with head and shanks, said shank being adapted to extend through the blank and to engage in the bores for guiding the cutting member, and a threaded carrier drivingly connected with said driving screw to urge said tubular die and said cutting member towards each other for cutting the blank.

3. A hand tool for forming holes in sheet material comprising, a male die and a female die having cooperating cutting edges, said female die having an annular bevelled cutting edge disposed at the inner periphery of the die, said bevel being of such pitch that it will penetrate sufficiently to locate the burr formed by the severing action of the dies intermediate of the surfaces of the blank and provide a resistance when substantially at said burr position that is greater than the shearing strength of the material, means for aligning said dies, and means for urging them relatively towards each other, to cause said knife edge to become imbedded in the material to be cut and to thereafter shear the material delimited by the said knife edge.

4. A hand tool for forming holes in sheet material comprising, a male die, a female die, said dies having cooperating cutting edges and concentric bores therein, said female die having an annular bevelled cutting edge with the surface of the bevel converging toward and intersecting with the inner surface of the die, said bevel being of such pitch that it has less resistance than the male member to relative motion for a predetermined depth of cut, but has a greater resistance than the male member beyond said depth of cut to thereby provide a severance of the material intermediate of the plane surfaces thereof, one of said dies having its cutting edge projecting from a plane normal to the axis of said die, aligning means adapted to extend through said bores and the blank to be cut by said dies, and screw means for urging said dies towards each other, thereby cutting said blank.

5. A hand tool comprising, a male and female member adapted to receive a sheet of material therebetween, said male member being formed with a convex conical surface for centering said cutting members with respect to an opening in said material, said dies having cooperating cutting edges and concentric bores therein, aligning means adapted to extend through said dies and opening for aligning the same, and screw means for urging said dies towards each other, thereby cutting said sheet material.

WILLIAM O. REESER. 60

CERTIFICATE OF CORRECTION.

Patent No. 2,176,943.

October 24, 1939.

WILLIAM O. REESER.

It is hereby certified that error appears in the printed specification of the above numbered patent requiring correction as follows: Page 2, first column, line 31, strike out the words "thereof to receive the slug 8 to be cut from the" and insert the same after "portion" in line 29; and that the said Letters Patent should be read with this correction therein that the same may conform to the record of the case in the Patent Office.

Signed and sealed this 16th day of January, A. D. 1940.

Henry Van Arsdale,
Acting Commissioner of Patents.
